UNITED STATES PATENT OFFICE.

OTIS W. DODGE, OF NEW YORK, N. Y.; CHARLES W. STEVENS, ADMINISTRATOR OF SAID
OTIS W. DODGE, DECEASED, ASSIGNOR TO WALTER H. BOWES CO., OF PORT CHESTER,
NEW YORK, A CORPORATION OF NEW JERSEY.

COUPLING FOR DRAIN-PIPES OF STEAM-HEATED DRYING-CYLINDERS.

1,310,391.

Specification of Letters Patent. Patented July 15, 1919.

Application filed June 28, 1916. Serial No. 106,388.

To all whom it may concern:

Be it known that I, OTIS W. DODGE, a citizen of the United States, residing at New York, in the county of New York and State 5 of New York, have invented certain new and useful Improvements in Couplings for Drain-Pipes of Steam-Heated Drying-Cylinders; and I hereby declare that the following is a full, clear, and exact description 10 thereof, reference being had to the accompanying drawings, which form part of this specification.

This invention is an improvement in apparatus such as described in my Patent No. 15 977,376 dated November 29, 1910, for removing moisture such as water of condensation from steam heated drying cylinders and the like. The object of the present invention is to provide a novel selfadjusting 20 compensating connection between the main drain pipe or reservoir within the drying cylinder and the discharge pipe which conducts water therefrom to a point exterior to the cylinder, so that such connection will 25 not be injuriously affected by slight eccentric displacement of such pipes, or relative axial inclination of one pipe to the other; such improvements also insure a simpler and more durable connection between 30 the interior and exterior drain pipes or reservoir, and obviate or greatly lessen the liability of breakage of the pipe connections should the pipes become slightly eccentrically displaced or out of true axial 35 alinement.

I will explain the invention more fully with reference to the accompanying drawings which illustrate so much of the apparatus as is necessary to impart a clear understanding 40 of the invention.

In said drawings:—

Figure 1 is a longitudinal sectional elevation through part of a steam heated drying cylinder showing the steam supply and 45 drainage connections.

Fig. 2 is an enlarged sectional view through the coupling between the main and auxiliary drainage pipe.

Fig. 3 is an enlarged transverse section 50 on the line 3—3, Fig. 2.

The drying cylinder 1 may be of any suitable construction, and is usually provided with heads having trunnions by which the cylinder may be rotatably mounted in suitable 55 bearings as described in my said patent.

The trunnion 1^c of the head 1^b is shown as hollow, and through this hollow trunnion steam is admitted into the cylinder and the water of condensation is removed as herein-after explained.

Mounted within such cylinder is a drain pipe 3 which may be supported on spiders 2 attached to the heads of the cylinder, so that said pipe is supported axially of the cylinder; this pipe 3 may be closed at its end 60 farthest removed from head 1^b but is open at the end adjacent said head, and to this open end is usually connected a smaller discharge pipe as 3^a which extends outwardly through the bore of the trunnion 1^c and is 65 connected to an outer discharge pipe.

As shown the pipe 3^a passes through the trunnion and into a chamber 8^b in a casting 8 in the usual manner, said casting 8 being attached to the outer end of the trunnion by 70 a suitable stuffing box 10 that allows the trunnion to rotate while the casting 75 remains stationary. The chamber 8^b in casting 8 connects with a pipe 8^c by which the water of condensation is conducted to any 80 suitable point of discharge. The casting 8 has another chamber 8^a beside chamber 8^b, chamber 8^a being connected by a pipe 8^e with a boiler or other suitable steam generator. The chamber 8^a communicates with the 85 bore of the trunnion 1^c through a sleeve 8^d attached to casting 8 and passing through the stuffing box 10 so that the cylinder can rotate while the casting 8 is stationary.

Within the cylinder and connected with 90 the pipe 3, at suitable intervals apart, are the inner ends of preferably convolutely bent pipes 3^e. The outer end of each pipe 3^e is connected to a scoop member 3^g; each scoop preferably being so constructed that 95 all the material which is taken up by a scoop is directed into its pipe 3^e and by the latter ultimately delivered into the pipe 3.

In practice I prefer to arrange a series of 100 scoops 3^g within the cylinder such series of scoops extending substantially in line the entire length of the cylinder; and as each scoop is connected by its convolutely bent pipe 3^e to the drain pipe 3 the scoops will 105 take up water of condensation and discharge same into the pipe 3 as the scoops rotate with the cylinder, after the manner described in my patent aforesaid. The general construction and arrangement of the 110

cylinder, drain and discharge pipes, convolute pipes and scoops shown in the drawings is fully described and claimed in my application.

5 It will be seen that when the cylinder is rotated in the proper direction any water in the cylinder will be picked up by the scoops 3^g and directed to the pipes 3^e and ultimately discharged thereby into the central pipe 3, from which the water will pass to the pipe 3^a; and thence conducted through the trunnion 1^e to pipe 8^e.

It sometimes happens that the pipe 3 becomes slightly eccentric to the cylinder or 15 out of true alinement with the pipe 3^a and as the outer end of the pipe 3^a is confined in the casting 8 should the pipes 3, 3^a become slightly displaced or deflected axially a strain is produced upon the joint between 20 the pipes 3 and 3^a, and it has sometimes happened that the connection which has been heretofore provided between these pipes has been broken and as a result the water is not properly discharged from the 25 cylinder, and this causes great annoyance; and the object of my present invention is to provide a self adjusting compensating connection between the pipes 3 and 3^a within the cylinder which will prevent any breaking 30 or leaking at the joint between pipes 3, 3^a in case they are not truly alined axially, or should become axially displaced or out of alinement for any reason after they are installed. For this purpose I preferably attach 35 to the end of the pipe 3 a cap-shaped casting 7 adjacent the trunnion 1^e which casting may be internally screw-threaded to engage the pipe 3 or otherwise water-tightly connected thereto so as to rotate therewith.

40 This cap casting closes the end of the pipe 3 but it has an axial outlet opening 7^b in its end, and is provided with a peripheral flange 7^a on its outer end to which may be secured a cupped plate 7^d having an axial opening 7^f slightly larger in diameter than the pipe 3^a and also having a flange 7^e fitted against flange 7^a and secured thereto by bolts 7ⁿ. The opposed faces of the cap 7 and cup plate 7^d are concaved and between 45 them is formed a socket or chamber 7^h in which is confined a ball-member 3ⁿ fast to the inner end of the pipe 3^a, said ball member being preferably provided with a threaded opening so that it can be screwed upon the end of the pipe 3^a as shown. The ball-member 3ⁿ and the opposed parts of the cap and cup plate between which it is confined forms practically a ball and socket connection between the pipes 3 and 3^a. The 50 side walls of the socket 7^h in which the member 3ⁿ is confined are preferably concaved on arcs slightly greater than the curvature of the arcs of the opposed faces of the ball-member 3ⁿ see Fig. 2, so that a 55 slight rocking motion is permitted the mem-

ber 3ⁿ within the chamber 7^h, and this permits slight axial displacement or angularity of the pipes 3 and 3^a relative to each other. This peculiar self adjusting compensating joint between pipes 3, 3^a permits sufficient 70 relative axial deflection of said pipes without putting any undue strain upon them or upon the connections of pipe 3^a with the casting 8. This construction obviates any danger of the connection between pipes 3, 3^a 75 breaking, and insures proper drainage of the water from the pipe 3 through pipe 3^a to the outlet, and thus insures that the cylinder will be properly drained even if the pipes 3, 3^a should be or become slightly eccentric to each other or out of alinement 80 when the cylinder is in operation.

The pipes 3 and 3^a are generally made of iron; the socket members 7, 7^d may be of cast iron and the ball-member 3ⁿ may be of 85 bronze or brass. By means of this ball and socket connection the outer end of pipe 3^a (which in practice is about 30 inches long) might be deflected from one-half to three-quarter inch off the axial line of the drain 90 pipe 3 without producing any injurious strain on its connection with the pipe 3.

In the practical operation of various types of drying cylinders as heretofore made great trouble has been experienced in 95 maintaining a proper connection between the discharge pipe and the scooping or draining means inside of the cylinder; my invention provides a flexible or self-compensating connection inside the drier between the scooping or draining means inside the cylinder and the discharge pipe leading out of the cylinder so that slight axial displacement of the parts, as above mentioned, will not injuriously affect the 100 connection.

This novel connection and location thereof facilitates assemblage of the parts, and also obviates any danger of breakage in 110 case the workman in installing pipe 3 within the cylinder should fail to mount it accurately axially therein, or truly centrally thereof at both ends. The outside of the drying cylinder is always turned true, but there may be a variation in thickness of its 115 shell, and when the brackets 2 are secured therein, which is usually done from inside of the cylinder, the pipe 3 might be slightly eccentric to the axis of the cylinder; and while such eccentricity might not be sufficient to prevent making the ordinary rigid screw-threaded coupling connection between pipes 3 and 3^a, yet if such connection was made and the pipes 3, 3^a were not in true 120 axial alinement or work out of such alinement an immediate strain would be put upon the connection which would ultimately produce breakage thereof and allow water of condensation to escape back into the cylinder instead of passing out of same, and 125 130

any such danger is entirely obviated by the present invention.

While I have described the invention as applied to apparatus of the character referred to in my aforesaid Patent No. 977,376, it is applicable to other kind of driers in which the water of condensation is removed from a drain pipe or collector in the cylinder through an axial discharge pipe extending through one of the cylinder trunnions, and I do not consider the invention restricted to use with the said patented construction or the specific arrangement of parts shown in the drawings.

15. What I claim is:

1. In combination with a drying cylinder having internal draining means, a discharge pipe extending outside the cylinder, and a compensating ball and socket connection within the cylinder between the internal draining means and the inner end of the discharge pipe.

2. In combination with a drying cylinder having internal draining means, an axially disposed discharge pipe extending outside the cylinder, and a ball and socket connection within the cylinder between the draining means and the inner end of the discharge pipe.

3. In combination with a drying cylinder having internal draining means; an axially disposed discharge pipe extending through one of the cylinder trunnions, and a compensating ball and socket connection within the cylinder between the draining means and the inner end of said discharge pipe.

4. In combination with a drying cylinder having an axially disposed drain pipe, and an axially disposed discharge pipe extending through one of the cylinder ends; of a self-adjusting compensating connection within the cylinder between the drain pipe and the inner end of the discharge pipe within the cylinder.

45. 5. In combination with a steam heated cylinder having a hollow trunnion, an axially disposed drain pipe within the cylinder and a discharge pipe extending through the trunnion of a self-adjusting compensating connection within the cylinder between the inner end of the discharge pipe and the adjacent end of the drain pipe within the cylinder.

55. 6. In combination with a steam heated cylinder having an axially disposed drain pipe, and an axially disposed discharge pipe extending through one of the cylinder ends, of a ball and socket joint connection within the cylinder between the drain and discharge pipes.

7. In combination with a steam heated cylinder having an axially disposed drain pipe within it and a discharge pipe extending out of the cylinder; of a cap attached to one end of the drain pipe, a cup-plate attached to the outer end of the cap, and a ball-member attached to the inner end of the discharge pipe and confined between the cap and the cup-plate and forming therewith a self-adjusting compensating ball and 65 socket connection within the cylinder between the drain and discharge pipes.

8. In combination with a steam heated cylinder having a hollow trunnion, an axially disposed drain pipe within the cylinder, 75 a discharge pipe extending through the trunnion, a cap attached to one end of the drain pipe, a cup-plate attached to the outer end of the cap, and a ball-member attached to the inner end of the discharge pipe and 80 confined between the cap and the cup-plate and forming therewith a self-adjusting compensating ball and socket connection within the cylinder between the drain and discharge pipes.

85. 9. In combination a cylinder, a pipe therein, a tubular cap adapted to be fitted to one end of said pipe and having an opening in its end, a recess in its outer face, and a flange surrounding said opening and recess; 90 a cup-plate having a recess and an opening, and a flange surrounding the opening adapted to be bolted to the flange of the cap, the space between the opposed recessed faces of the cap and cup-plate forming a socket, 95 a drain pipe extending out of the cylinder; and a ball-member fitted in said socket and adapted to be secured to the inner end of the drain pipe to form a yieldable compensating connection within the cylinder between 100 said pipes.

10. In combination a cylinder, a pipe therein, a tubular cap adapted to be fitted to one end of the pipe and having a recess and an opening in its end, a recess in its outer end, and a flange surrounding the recess and opening; a cup-plate having an opening, and a flange adapted to be bolted to the flange of the cap-member, the space between the opposed recessed faces of the cap 105 and cup-plate forming a socket, a drain pipe extending out of the cylinder; and a ball-member adjustably fitted in said socket and adapted to be secured to the end of said drain pipe within the cylinder whereby a 110 yieldable compensating connection is formed between said pipes.

In testimony that I claim the foregoing as my own, I affix my signature.

OTIS W. DODGE.
